UNITED STATES PATENT OFFICE.

OSCAR DELLMONT WILLIS AND EDWIN WOOD FELIX, OF HUNTINGTON, WEST VIRGINIA.

HOLDER.

Application filed June 20, 1924. Serial No. 721,248.

To all whom it may concern:

Be it known that we, OSCAR D. WILLIS and EDWIN W. FELIX, citizens of the United States, and residents of Huntington, in the county of Cabell and State of West Virginia, have invented new and useful Improvements in Holders, of which the following is a full, clear, and exact description.

The present invention relates to new and useful improvements in attachments for cigarette packages and it pertains more particularly to an attachment in the form of a match holder and carrying means adapted for use in connection with a cigarette package.

It is one of the primary objects of the invention to provide a device of this character which may be readily attached to and removed from a cigarette or similar package.

It is a further object of the invention to provide means whereby the device is retained in position upon the cigarette package.

It is a still further object of the invention to associate with the match-carrying means means for permitting of the discharge of the cigarettes contained in the package to which the device is attached.

With the above and other objects in view reference is had to the accompanying drawing, in which—

Figure 1 is a perspective view of a cigarette package showing the match-carrying attachment in place thereon;

Figure 2 is a perspective view of the match-carrying attachment; and

Figure 3 is a longitudinal sectional view taken on the line 3—3 of Figure 1.

Referring more specifically to the drawing, the reference numeral 5 designates a cigarette package which is of the ordinary construction.

The reference character A designates a substantially U-shaped member having a base portion 6 and two legs or sides 7 and 8. Each of the legs 7 and 8 is cut as at 9 to provide resilient tongues 10 and said resilient tongues 10 are formed with a serrated free end 11. The base 6 of the U-shaped member is provided with an opening 12 and said opening constitutes means whereby the contents of the package may be discharged from the U-shaped member.

The leg 8 of the U-shaped member is provided on its side edges with a plurality of

integral clips 13 and the said clips are bent inwardly of the leg 8, as designated by the reference numeral 14. In bending these clips 13 inwardly of the leg 8 they are spaced from said leg or occupy a position parallel therewith for a purpose to be hereinafter described.

The reference character B designates a match book and said match book is adapted for attachment to the U-shaped member by passing its back 15 beneath the inwardly turned clips 13, as more clearly shown in Figure 1.

In use the U-shaped member A is adapted to embrace a cigarette package with the base 6 of the U-shaped member closing the opened end of the package. This presents the opening 12 heretofore mentioned through which cigarettes, such as designated by the reference character C in Figure 1, may be discharged.

With the U-shaped member upon the package in this position a match book B is secured to the U-shaped member by passing its back beneath the clips 13 as heretofore described.

When the U-shaped member is positioned upon the cigarette package the serrated end of the resilient tongues 10 engage the open end of the cigarette package, as indicated by the reference character D in Figure 3, and prevent a movement of the cigarette package relative to the U-shaped member to a point where the opened end of the cigarette package would engage the base 6 of the U-shaped member A.

From the foregoing it is apparent that the present invention provides a new and novel device for attaching a match book to a cigarette package, and at the same time the device provides a closure for the cigarette package and permits of discharge of the cigarettes therefrom.

What is claimed is:

1. A holder comprising a U-shaped element consisting of two sides and a base; and a resilient tongue having teeth at the free extremity thereof on each of said sides, the tongues coacting to cause the teeth thereof to engage the opposite sides of a package to hold the package between the sides.

2. A holder stamped, bent and formed from a single piece of material to provide a U-shaped element consisting of an apertured base and sides; and resilient tongues each

having angularly disposed teeth at its extremity, said resilient tongues being arranged on said sides respectively opposite each other and capable of coaction to hold a package between the sides by virtue of the resulting impalement of said teeth in the package.

3. A holder comprising a U-shaped element consisting of two sides and a base; a resilient tongue having teeth at the free ex-

tremity thereof on each of said sides, the tongues coacting to cause the teeth thereof to engage the opposite sides of a package to hold the package between the sides, and a pair of clips at the opposite side edges of one of the sides for releasably retaining a second package.

OSCAR DELLMONT WILLIS.
EDWIN WOOD FELIX.
